UNITED STATES PATENT OFFICE

OLIVER W. VANDINE, OF CARNEIRO, KANSAS

CULTIVATOR DISK SCRAPER

Application filed June 26, 1931. Serial No. 547,122.

This invention relates to an attachment for a conventional disk type cultivator, particularly of the two disk type, in the form of an attachment which is readily installable and 5 easily removable, which will effectively clean the disk of the cultivator and prevent their clogging with mud and the like, so as to enable the cultivating of a field much sooner than is usually possible after a rain or damp 10 period.

It is an object of this invention to provide a device of the character described above which is composed of few and simple and rugged parts and which is not only efficient in action, 15 but which is durable and does not require frequent replacement.

It is also an object of this invention to provide a device of the character described which can be cheaply and easily manufactured, which is adjustable, and which may be 20 made in right and left hand forms according to requirements.

These and other objects of the invention, its nature, and its composition and arrangement and combination of parts will be readily 25 understood by anyone acquainted with the art to which this invention relates upon consulting the following description of the drawings.

30 In the drawings:

Figure 1 is a general perspective group view of the device of the invention installed in connection with a conventional disk cultivator.

35 Figure 2 is a top plan view thereof.

Figure 3 is an elevational view of the scraper blade.

Figure 4 is a perspective view of the adjustable cross bar.

40 Figure 5 is a view of the blade holding bracket.

Figure 6 is a perspective view of the V-shaped bracket supporting the blade structure on the cross bar.

45 Figure 7 is a view of one of the bolt locks, and

Figure 8 is a view of another of the bolt locks.

The numeral 5 refers generally to a cultivator disk supported on the usual shaft 6 by

the vertical shank 7 mounted in the usual casting generally designated 8, and the numeral 9 refers generally to the scraper attachment of the invention.

The device of the invention comprises a 55 clamp composed of the block 10 of generally circular form and provided on one face with the radially arranged grooves 11 to provide a gripping surface, and on the other face with the depression 12 of the same radius of curvature as the eye 13 of an eye bolt 14 passed through the block 10. The eye 13 is passed about the vertical shank 7, and the bolt 14 is passed through one of a series of holes 15 in the horizontal cross bar generally designated 16, and nut 17 is to be drawn against the horizontal cross member 16 so as to clamp the upright shank 7 in the eye 13 and against the block 10. This clamping action also solidly 60 clamps the cross bar 16 in the desired adjusted position. At one end of the cross bar 16 and on the forward face thereof is bolted a V-shaped bracket generally designated 18, whose aperture is less than ninety degrees. The V-shaped bracket is provided with bolt 75 holes 19 and 20 to receive bolts, whose nuts are adapted to be locked by the V-shaped lock generally designated 21 which has the deflected end portions 22 for engaging one side of the nuts, the lock adapted to be placed inside 80 of the V-shaped bracket 18 as seen in Figure 1.

Upon the upper surface of the horizontal plate of the bracket 18 is supported an L-shaped blade holder 23 which has the bolt holes 24 in the bottom portion and 25 in the upright portion. Bolts 26 are passed through the holes 25 and 25a in the upright portion of the blade holding bracket affording angular 85 adjustment of the blade and they are adapted to be locked by a locking strip 27 after they pass through a plurality of holes 28 in a generally rectangular scraper blade 29, so as to support the blade in vertical position in engagement with the disk 5. The scraper blade 29 is vertically elongated and is provided with a curvate edge, and may be otherwise deformed to properly engage the contour of the disk 5.

95 The above is thought to be a description 100

sufficiently in detail to enable anyone acquainted with the art to which this invention relates to make, construct and use the same, and it is therefore thought that further description is unnecessary.

5 Inasmuch as various changes and modifications might be made in the device of the invention to make it to suit different types and makes of the disk machines, it is to be definitely understood that I do not desire to limit the application of this invention to the particular modifications set out herein to illustrate the principles thereof, and any change or changes may be made within the spirit and 10 scope of the invention.

15 Having thus described my invention, what I claim as new is:

1. A disk scraper attachment for cultivators and the like comprising a clamp adapted 20 to be attached to the vertical shank of one of the disk supports of the cultivator or the like, a longitudinally adjustable cross bar also held by the clamp, an adjustable angle bracket on the cross bar, an adjustable blade bracket 25 on the angle bracket, and a vertically adjustable scraper blade on the blade bracket.

2. A disk scraper attachment for cultivators and the like comprising a clamp adapted to be attached to the vertical shank of one of 30 the disk supports of the cultivator or the like, a longitudinally adjustable cross bar also held by the clamp, an adjustable angle bracket on the cross bar, an adjustable blade bracket on the angle bracket, and a vertically adjustable 35 scraper blade on the blade bracket, said clamp being capable of being vertically adjusted on said shank.

3. A disk scraper attachment for cultivators and the like comprising a clamp adapted 40 to be attached to the vertical shank of one of the disk supports of the cultivator or the like, a longitudinally adjustable cross bar also held by the clamp, an adjustable angle bracket on the cross bar, an adjustable blade bracket 45 on the angle bracket, and a vertically adjustable scraper blade on the blade bracket, said clamp being capable of being vertically adjusted on said shank, and said cross bar, angle bracket and blade bracket cooperating to permit 50 angular positioning of the scraper in any direction.

In testimony whereof I affix my signature.
OLIVER W. VANDINE.
